UNITED STATES PATENT OFFICE.

OLE G. LARSON, OF DULUTH, MINNESOTA, ASSIGNOR OF ONE-HALF TO DAVID R. BLACK,
OF DULUTH, MINNESOTA.

SELF-LUBRICATING DIE-STOCK.

1,137,496.

Specification of Letters Patent. Patented Apr. 27, 1915.

Application filed January 4, 1915. Serial No. 426.

To all whom it may concern:

Be it known that I, OLE G. LARSON, a citizen of the United States, residing at Duluth, in the county of St. Louis and State of Minnesota, have invented certain new and useful Improvements in Self-Lubricating Die-Stocks, of which the following is a specification, reference being had to the accompanying drawings.

My invention relates to die stocks and more particularly to a die stock provided with means whereby a lubricant may be applied to the dies.

The primary object of my invention is the provision of a die stock so formed that one handle of the die stock constitutes a reservoir for lubricant whereby lubricant may be applied to the cutting dies.

A further object of the invention is the provision of a lubricant containing a reservoir formed in the handle of the die stock and the provision of means disposed in said reservoir whereby the lubricant may be forced out from the reservoir and on to the cutting edges of the dies by a pressure of the operator's finger.

Still another object of the invention is to so construct the reservoir that it may be readily cleaned, when necessary and that the handle which forms the reservoir may be removed from the body of the stock itself.

Other objects will appear in the course of the description.

Figure 1 is a plan view of a die stock constructed in accordance with my invention; and Fig. 2 is a fragmentary plan view of a portion of the body of the stock and the handle, the handle being in section to show the interior of the reservoir.

Referring to these figures, 2 designates a die stock of any ordinary or usual construction, having sockets projecting therefrom at diametrically opposite points, as shown at 3, each of which is interiorly screw-threaded. One of these sockets receives in it the usual handle 4 and the other the handle 5. This handle 5, for a portion of its length, at its outer end has the same diameter as the handle 4 and is hollow. The inner extremity of the handle 5 is exteriorly screw-threaded, as at 6 for insertion in the socket 3 and between the outer end of the handle and this inner end 6, the handle is enlarged 55 to form a reservoir 7. Preferably this res-

ervoir 7 and, therefore, the handle is formed of two sections 8 and 9, these sections having screw-threaded engagement with each other as at 10. This screw-threading of the sections provides a shoulder 11 between 80 which and the end of the section 9 there is confined a diaphragm 12 of thin metal or other suitable material. Attached to the diaphragm 12 and extending out through the outer end of the handle is an actuating 65 rod 13, the outer end of which passes through a plug 14 and has attached to its extremity a button 15. In order to provide for the filling of the reservoir 7, I form the portion 8 with a filling opening 16 closed 70 by a screw-threaded closure or plug 17.

The operation of my invention will be obvious from what has gone before. The die and stock is to be used in the ordinary manner and, when it is desired to oil the 75 stock, the button 15 is pressed inward, forcing inward the diaphragm 12 and causing the oil to be expelled through the contracted nozzle 18 into the contracted bore 19 formed in the adjacent portion 3. The button 15 80 should be pressed inward when the handle is in a vertical position.

It will be seen that with my device, the oiling of the die stock is entirely within the control of the operator and that the reservoir 7 may be readily filled. It will also be obvious that the handle 5 may be readily detached from the body of the stock, as may the handle 4. Again, it will be seen that by detaching the two sections 8 and 9 from 85 each other, the diaphragm 12 which is held to the rod 13 by nuts 20, may be readily detached and that full access is had to the interior of the reservoir 7, so as to thoroughly clean it when necessary or to put in a new 90 diaphragm, when required.

My invention is simple, can be readily applied to stocks already in use by simply providing a new handle for this stock and it is entirely effective in practice.

Having thus described this invention, what I claim as new and desire to secure by Letters Patent, is:-

1. A die stock having a hollow handle formed to provide a lubricant reservoir, a diaphragm disposed within the reservoir, and means extending through the handle for actuating said diaphragm to eject oil from the reservoir.

2. A die stock having a hollow handle,

- one portion of the handle being enlarged to form a lubricant chamber, a diaphragm disposed within the chamber, a rod connected with the diaphragm and extending out through the handle, and a button mounted upon the rod whereby the diaphragm may be actuated to eject the oil from the reservoir. 5
3. A die stock including a hollow handle enlarged at one portion to form a lubricant reservoir, said handle being made in two sections, the joint between the sections extending through the reservoir, a diaphragm disposed between said sections and within 10 the reservoir, a rod attached to the diaphragm and extending out through the outer end of the hollow handle, and a button attached to said rod. 15
4. A die stock including a body having 4.

outwardly extending oppositely disposed handle sockets, a removable handle in one of said sockets, and a removable handle for engagement in the other socket, the last named handle being hollow and having an enlarged portion intermediate its length, a metallic diaphragm removably disposed within said enlarged portion, a rod extending out through the end of the handle and provided with means whereby the diaphragm may be actuated, and means whereby the reservoir may be filled. 20 25

In testimony whereof I hereunto affix my signature in the presence of two witnesses.

OLE G. LARSON.
